US00D881167S

(12) **United States Design Patent** (10) **Patent No.:** **US D881,167 S**
(45) **Date of Patent:** **** Apr. 14, 2020**

(54) **STAND FOR LOUDSPEAKER**

(71) Applicant: **SHENZHEN HEALTHWELL TECHNOLOGY CO., LTD**, Shenzhen (CN)

(72) Inventor: **Jianpo Jiao**, Shenzhen (CN)

(73) Assignee: **SHENZHEN HEALTHWELL TECHNOLOGY CO., LTD.**, Shenzhen (CN)

(**) Term: **15 Years**

(21) Appl. No.: **29/717,311**

(22) Filed: **Dec. 16, 2019**

(51) LOC (12) Cl. **14-01**

(52) U.S. Cl. **D14/224**
USPC .....

(58) **Field of Classification Search**

USPC D14/224, 224.1, 217, 209.1, 204, 253, D14/211, 448, 447, 227, 203.8, 229, 451, D14/371, 452, 457, 454, 126; D8/373, D8/363, 349, 354, 380; D21/333; D16/242; 108/150, 159, 158; 248/917, 248/278.1, 288.51, 220.21, 324, 316.1; 455/90.3, 575.1, 569.1

FOREIGN PATENT DOCUMENTS

EM 000842224-0001 * 12/2007

Primary Examiner — Paula Allen Greene

(57) **CLAIM**

The ornamental design for a stand for loudspeaker, as shown and described.

DESCRIPTION

FIG. 1 is a perspective view of a stand for loudspeaker showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the drawings depict portions of the stand for loudspeaker that form no part of the claimed design.

1 Claim, 8 Drawing Sheets
